CLAUDE H. COOK, HARRY J. LEWIS, AND CHARLES E. LEWIS, OF CLEVELAND, OHIO.

ELECTRIC STOVE.

Application filed August 4, 1921. Serial No. 489,828.

To all whom it may concern:

Be it known that we, CLAUDE H. COOK, HARRY J. LEWIS, and CHARLES E. LEWIS, citizens of the United States, residing at Cleveland, in the county of Cuyahoga and State of Ohio, have invented certain new and useful Improvements in Electric Stoves, of which the following is a specification.

This invention relates to improvements in electric stoves, especially adapted for use on the serving table and other such uses.

The object of this invention is to provide such a stove which is simple in structure and hence not costly to manufacture, highly efficient and durable.

Fig. 1 is a plan view of our invention; Fig. 2 is an end elevation partly broken away; Fig. 3 is an inverted plan view of a corner portion of our device; Fig. 4 is a section on line 4—4 of Fig. 3; Fig. 5 is a perspective of one of the legs; Fig. 6 is a detail view of the integral tongue formed on the corners of the brace plate for engagement with the legs; and Fig. 7 is an inverted plan view of the clip connection between the wires.

The insulated electric wires indicated at 1 are led in under the asbestos pad 2 to the binding posts 3 at the two ends of the electric heating coil 4 secured on the top face of the asbestos pad by means of the U-shaped clamps 5 of drawn steel extending therethrough and turned out at the other side. The pad 2 is provided with a coating of silicone of soda to prevent discoloring of the same by the extremely high heat of the resistance coil contacting therewith and incidentally to improve the appearance of the device. The asbestos pad 2 is supported by means of the legs 6 which are rounded at the corners and provided at the top with the integral ears 7 formed so as to support the pad 2. These ears have parallel, horizontal, spaced portions 7^a and 7^b for receiving the corner edge portions of the pad. The four legs are of exactly the same structure and are preferably stamped up from light metal. The legs are provided also with integrally formed loops 8 struck inwardly therefrom for engagement by the tongues 9 formed integral upon the corners of the deflector and brace plate 10 which extends between the legs. The ears 9 extend downwardly from the base plate and are bent slightly in-

wardly as clearly illustrated in the drawings. This deflector and brace plate is also provided with a downwardly extending flange 10^a which is engaged by the legs but which, however, is omitted at the corner portions where the tongues 9 are provided.

The grate or grid member 12 is formed of pressed metal of suitably light grade and preferably with rounded corners, the bars 12^a being formed integrally therewith in the same manner. This grid member has the outwardly extending flange 13 and an apron or flange 14 extending about the four sides thereof and adapted to depend slightly below the ears 7 of the legs 6 when assembled. The corner portions of the flange 14 are swaged slightly inwardly as indicated at 15 so as to have releasable snap lock engagement with the ears 7 of the legs upon assembling the parts.

In assembling this structure the tongues 9 are engaged in the loops 8 and the ears 7 are engaged with the corner portions of the asbestos pad by swinging the legs inwardly about a center at the point of engagement between the loops 8 and the tongues 9. Then the grid 12 is applied to the top of the legs by snap engagement which secures the upper ends of the legs in locked assembly. According as may be desired, the tongues 9 may be bent inwardly just sufficient for releasable engagement with the loops 8 so that the parts can be disassembled by reversing the procedure above recited for assembly, or, the tongues may be bent inwardly still further after assembling the parts so as to more securely lock the parts together.

Referring now in detail to the matter shown in Fig. 7 and also in Fig. 1, the metal clip 16 has partially closed tubular arms 17 extending about and gripping the tubular sections of asbestos 18 through which extend the individual wires, and the other arm 19 of the clip grips the wires by means of the tongues 19^a and 19^b. The clip has the portion 20 depressed, as viewed in Fig. 1 so as to lie in a plane approximately through the diameter of the asbestos tubes. The looped ends of the wires for securing to the binding posts are indicated at 21. Sufficient air is permitted through the asbestos tubes and at the same time the clip maintains the wires in proper spread relation. The top of the clip also protects the insulation of the wires

against wear which would otherwise be caused by rubbing against the edge of apron 14.

The plate 10 deflects any heat which reaches it through the asbestos pad and thereby serves to protect the table upon which the stove rests and also to conserve the heat for cooking.

Thus we have provided an inexpensive and yet a durable structure which can be readily assembled by the user and in which the pad and coil can be renewed as a separate unit. An extremely high efficiency is also obtained in the degree of heat reflected by the pad.

Other advantages flowing from the improved structure above described are thought to be obvious to one who is skilled in the art to which the invention relates.

What we claim is:

1. An electric stove, comprising a heating element, a plate member therefor formed of non-conducting heat-resisting material, detachable legs for engaging and supporting said plate member, and a brace plate having positive interlocking and detachable connection with said legs.

2. An electric stove, comprising a heating element, a plate member therefor formed of non-conducting heat-resisting material, detachable legs having integrally formed ears for engaging the marginal portions of said plate member, and a brace plate having positive interlocking and detachable connection with said legs.

3. An electric stove, comprising a heating element, a plate member therefor, detachable legs for engaging and supporting said plate member, a brace plate extending between said legs, said brace plate and legs being provided with means integral therewith for positively securing the same together.

4. An electric stove, comprising a heating element, a plate member therefor, legs provided with ears having supporting engagement with said plate member, said legs being provided with eyes upon the inner faces thereof, and a brace plate having tongues for locking engagement with said eyes.

5. An electric stove, comprising a heating element, a plate member therefor, legs provided with ears having supporting engagement with said plate member, and a brace plate, said legs and brace plate having integrally formed eyes and tongues for detachable interengagement.

6. An electric stove, comprising a heating element, a plate member therefor, legs for supporting said plate member, a brace plate spaced below said pad and engaging said legs, and a grid member above said plate member and having frictional bracing engagement with the upper end portions of said legs.

7. An electric stove, comprising a heating

element, a plate member therefor, legs having ears engaging the marginal portions of said plate member for supporting the same, and a grid member above said plate member and having detachable frictional engagement with said ears so as to secure the same in engagement with said plate member.

8. An electric stove, comprising a heating element, a plate member therefor, legs having ears engaging the marginal portions of said plate member for supporting the same, and a grid member above said plate member and having detachable snapping engagement with said ears so as to secure the same in engagement with said pad.

9. A knockdown stove, comprising grid-, heater-, deflector-, and leg members constructed and arranged for assembly by readily attachable and detachable connection, said heater member being connected to the leg members, and said leg and grid members being provided with integral interlocking parts to space the heater member from the grid member.

10. A knockdown stove, comprising grid-, heater-, deflector-, and leg members constructed and arranged for assembly by readily attachable and detachable means, the grid member having an integral skirt portion surrounding and telescoping over the leg members.

11. A knockdown stove, comprising a frame, including leg members, a heater member, and a deflector member attached to said leg members and spaced from said heater member thereby, and a grid member having a skirt portion telescoping around said frame.

12. A knockdown stove, comprising a structure including leg members, a heater member, and a deflector member attached to said leg members, and a grid member having a skirt portion telescoping around said structure, said grid member and structure including interengaging parts adapted to space the heater member from the grid member.

13. An electric stove, comprising a grid member provided with a skirt, and a heating member telescopically located with the skirt thereof, said grid and heating members being spaced apart.

14. An electric stove, comprising heater and deflector members co-operatively associated and supported in spaced relation from each other, and a grid member having a skirt portion and adapted to be detachably assembled with said heater and deflector members by telescoping the heater member within said skirt portion.

15. A stove, comprising a grid member having a depending skirt portion, and a heating element including an insulating plate located within said skirt portion and provided on the face adjacent to

said grid member with resistance wires, said plate substantially closing the bottom of the skirt and forming above it a heating chamber closed except where open through said grid.

16. An electric stove, comprising a grid and leg structure including a depending skirt portion and formed to provide a shoulder, and a heating element associated with 10 said structure and enclosed within the depending skirt portion and cooperatively related to said shoulder so as to space said heating element from the grid.

17. An electric heater, comprising a rigid 15 plate member formed of non-conducting heat resisting material, a resistance wire supported on its upper face, a support therefore comprising a plate lying beneath the first plate member, leg members and means 20 integral with said plate and leg members for detachably connecting and spacing the two plates from each other.

18. An electric heater, comprising a non-conducting heat resisting plate member, a 25 resistance wire on the upper face thereof, a grid member for supporting an article to be heated above said resistance wire, and means including a part integral with said grid member for spacing said grid and 30 plate members from each other.

19. An electric heater, comprising a non-

conducting heat resisting plate member, a 35 resistance wire on the upper face thereof, detachable leg members embracing at intervals the edge of said plate member, and means surrounding the edge of the plate member and said leg members for locking the legs to the plate member.

20. In a heating stove, a rectangular shelf 40 member supporting legs positively and detachably connected to the corners thereof and extending above the same, a plate member carrying a resistance wire and connecting the upwardly extending ends of said legs, and means for releasably locking the 45 legs, shelf and plate members to each other.

21. In an electric heater the combination 50 of a bottom plate, a top plate, an intermediate insulating plate, a heating element mounted on the insulating plate, and legs supporting said plate, said legs having projections on which the bottom and intermediate plates rest, and the top plate having a flange surrounding the edge of the intermediate plate and engaging the upper ends 55 of the legs.

In testimony whereof we hereby affix our signatures.
